SHELF TRIMMING

Moses Caplan, Boston, Mass.

Application February 5, 1934, Serial No. 709,720

4 Claims. (Cl. 41—10)

This invention relates to shelf trimmings for china closets, pantries and the like, and aims to provide a novel trimming having a shelf top covering and a shelf edge covering section, that will naturally tend to stay in position on the shelf, without being tacked or otherwise fastened, and resist the usual inclination to slide out of position on the shelf edge.

In the drawing of one embodiment of my invention illustrated and described herein:

Figs. 1, 2, 3, illustrate an exemplified plan, and a front edge and sectional views, respectively, partly broken away for convenience;

Figs. 4, 5 and 6, illustrate similar views, respectively, of a modified form;

Fig. 7 is a figure similar to Fig. 3, of a still further form of construction; and

Fig. 8, a still further modified form of the invention.

While shelf trimmings of various kinds have long been used, yet the usual form has comprised one or more sheets of material of suitable width, adapted to overlie the shelf front edge and hang down more or less closely to the front shelf edge, usually in an outward curve from the shelf edge.

These trimmings have had a tendency to slide on the shelf top, and thus get out of position, which tendency it is one object of my invention to overcome.

Referring first to Figs. 1 to 3, my novel trimming comprises a shelf top covering section 1, of either one or more thicknesses, herein one, of any suitable material as oil cloth, textile fabric, paper, or the like, to the front edge 2 of which is secured, in any manner, as by stitches 3, a strip of flexible binding 4.

This binding may comprise either two plies 5, 6, formed by folding the binding or bonding strip 4 lengthwise to provide a smooth, rear edge 7, or a single layer 5, with a selvage, may be used, if preferred. This ply 5 is then carried down vertically against the shelf cover edge, and then backward therefrom to form the ply 9, which, in turn, is folded upward and carried forward, parallel to ply 8, as ply 10.

This ply 10 may then, in turn, be folded upward and run backward as ply 11, parallel with and against the lower face of the sheet 1, Fig. 3, or ply 10 may, Fig. 7, end at the edge of the sheet 1, and a new sheet 12 of similar or different material or color, be laid parallel with ply 10, and in either case turned down against the edges of plies 9 and 10, as ply 13. This ply is then folded and turned upward and parallel thereto

as ply 14, over the top of the front edge sheet 15, the latter having an extra ply 16, if preferred, and again dropped down as ply 17, substantially parallel with the shelf edge 18, and stitched or otherwise secured to the front edge plies 15, 16, as at a, or, if preferred for any reason, again folded and turned upward as ply 19, as being more secure.

It will be noted that this form of construction provides a reinforced front edge trimming structure preferably of at least two plies of binding upon the upper and lower faces of the shelf cover sheet 1, a flexible, hinge-like ply 13 for the shelf edge cover 15, permitting the latter to naturally drop straight down and lie closely against the shelf edge, and form a joint or bond in the binding of such nature that the shelf top cover 1 and shelf edge material 15 readily conform to the shelf outline, with no tendency to move either way about the shelf corner 20.

There is thus provided a shelf edge trimming, comprising two multi-ply sections connected by a thin, as a single ply, section, that will stay in position, whereas the usual trimming edge will slide, or yield, so that the trimming easily becomes misplaced on the shelf. This trimming also may be made of contrasting color sections, as stated, or different kinds of material, and with the formation described present a bead-like edge to the eye.

In the embodiment shown in Figs. 4 to 6, inclusive, the shelf cover section 1 has on its edge the broad lower ply 24 folded at its rear edge forwardly to form ply 25, which, in turn, is carried down vertically about the edge 26 of the shelf cover 1, and folded rearwardly to form plies 27, 28, and stitched as at 29, or otherwise secured, the latter ply carried straight down and laid against the front edge of the shelf forming the plies 30, 31, the latter carried up over the edge 26 of the shelf edge cover 15 of one or more plies, and again brought down upon the outside thereof with folds or plies 32, 33, stitched or otherwise secured, as at 34, forming a cover binding with a recessed edge.

This binding structure for securing in proper relation the shelf top cover and shelf edge cover sheets, may obviously also be used, Fig. 8, to secure in right angle relation two sheets or core members 35, 36, for any purpose whatever, providing a novel binding structure with an outstanding bead 37, corresponding to the top cover edge, which structure may be subsequently stitched, as at 38, or otherwise secured, to a sheet 39 of material for any use, as in Fig. 8. Such

structure may conveniently be prepared and sold by the yard, of desired width, and to be stitched or secured, as stated, to any sheet material corresponding to the top and edge sections 1, 15, 5 respectively.

My invention is not limited to the precise embodiment thereof herein shown and described.

I claim:

1. Shelf trimming comprising, in combination, 10 a shelf-top-cover-section, a shelf-edge-cover-section, and a connecting hinge-like binding strip member, comprising a top-cover-section-upper-edge multi-ply binding area, a top-section-lower-edge multi-ply binding area, both the top cover edge binding area and the shelf top cover extended forwardly of the shelf edge, the lower edge binding area extended rearwardly of the cover edge, and folded downward to form a shelf-edge-cover-outer multi-ply binding area, and 20 then extended laterally and downwardly to form an edge-cover-inner multi-ply binding area.

2. Shelf trimming comprising, in combination, 25 a shelf-top-cover-section, a shelf-edge-cover-section, and a connecting hinge-like strip binding member, comprising a top-section-upper-edge multi-ply area; a top-section-lower-edge multi-ply, horizontal area extended rearwardly of the edge-cover-section, and folded closely to the cover section downwardly to form a shelf-edge-cover-outer multi-ply area and a shelf-edge-cover-inner multi-ply area folded adjacent to the top section cover, and at an acute angle to the horizontal area to align the top cover edge in substantially parallel relation with the shelf edge, 30 with the top cover edge and multi-ply areas forming a projecting bead at the shelf edge.

3. Shelf trimming comprising, in combination, 35 a shelf-top-cover-section, a shelf-edge-cover-

section, and a connecting hinge-like strip binding member, comprising a top-section-upper-edge multi-ply area; a top-section-lower-edge multi-ply horizontal area extended rearwardly of the edge-cover section forming an edge cover 5 positioning structure, and folded closely to the cover section downwardly to form a shelf-edge-cover-outer multi-ply area and a shelf-edge-cover-inner multi-ply area folded adjacent to the cover section, and at an acute angle to the horizontal areas forming a top cover positioning structure to align the cover edge in parallel relation with the shelf edge, with the multi-ply top and front edge areas at right angles to each other forming a shelf trimming with a recessed 10 edge.

4. Binding structure for securing a plurality of sheets of material to each other in substantially right angle relation with a bead at the joint, comprising a horizontal core strip 1 with a sheet of bonding material thereon folded longitudinally on itself to provide an area of a plurality of plies 5, 6; the front edge of ply 6 turned at right angles thereto and again folded longitudinally on itself against the opposite side of 20 the core sheet providing a multi-ply area 9, 10, 11, said multi-ply area secured to the core strip; said latter ply 11 turned at right angles, folded on itself longitudinally forming plies 13, 14; and again turned at substantially a right angle and 25 then turned again at a right angle downward to form a multi-ply area 11, 19, a second core of strip material 15 secured between the 13, 14 multi-ply area and the 17, 19 multi-ply area 30 either of said core strips with its multi-plies constructed to be secured to a desired sheet of body material.

MOSES CAPLAN.
